Howson and Howson

Patented Nov. 24, 1925.

UNITED STATES PATENT OFFICE.

HENRI CORBLIN, OF PARIS, FRANCE.

DIAPHRAGM COMPRESSOR.

Application filed September 20, 1923. Serial No. 663,821.

To all whom it may concern:

Be it known that I, HENRI CORBLIN, a citizen of the Republic of France, and a resident of Paris, France, have invented new and useful Improvements in Diaphragm Compressors, of which the following is a specification.

This invention relates to diaphragm compressors, more particularly intended for the compression of gases, of the type in which a diaphragm oscillates in a chamber having the general shape of a double cone, formed between two discs between which the diaphragm is secured.

Hitherto, with a view to pressing the diaphragm as accurately as possible against the surface of the disc carrying the suction and delivery valves, and thus obviating the formation of any objectionable clearance space, it has been sought to make the pump actuating the diaphragm displace a volume of liquid greater than that generated by the diaphragm between its two extreme positions in the compression chamber, that is to say when it is pressed against the lower and the upper discs respectively.

This result has been obtained, for example, as described in my United States Letters Patent No. 1,332,806, of March 2, 1920, by making the piston itself act as reservoir for the liquid and by fitting it with a lift-valve arranged so as to open at a given pressure and a snifter arranged so as to open at a given vacuum, in such a way as to allow of passing a portion of the liquid at a given pressure from the compression chamber into the reservoir-forming piston and vice versa.

According to the present invention, the volume of the compression chamber is greater than that generated by the stroke of the piston which causes the diaphragm to oscillate by the action of the liquid, and in order that the diaphragm may be pressed against the lower disc at the end of the delivery stroke of the piston, there is injected into the body or barrel of the pump during the stroke of the piston, either on the delivery or preferably on the suction stroke, a very small quantity of liquid which makes up for the leaks between the piston and the pump barrel, as well as the clearance that may exist or arise in the connecting rod ends, in the bearings, etc. For this purpose, a small pump with variable output, coupled to the crankshaft of the

compressor piston, delivers to the pump barrel the necessary quantity of liquid, this auxiliary pump taking up by suction the liquid which escapes from the main pump, either at the end of its delivery stroke through the valve mounted in the piston, or owing to leakage of the packing rings on the latter.

The liquid is with advantage cooled in any suitable manner before being delivered by the auxiliary pump into the barrel or cylinder of the compressor piston.

The accompanying drawing represents diagrammatically and in vertical axial section, but merely by way of example, one form of construction of the invention.

The compressor comprises two discs *a* *b*, bolted together at their peripheries, between which is clamped the diaphragm *c*, the latter being adapted to oscillate in the compression chamber *d* which has the general shape of a double-cone and is formed between the two discs *a* and *b*; the lower disc *a* carries the suction valve *e* and delivery valve *f*, operated by the displacement of the diaphragm *c* in the chamber *b*. This diaphragm is itself operated by the piston *h* displacing in the pump barrel *i* a volume of liquid, for example oil, acting upon the upper face of the diaphragm *c* by passing through openings *b*¹ formed in the central part of the upper disc *b*.

The piston *h* comprises a lift-valve *h*¹; the pump body or barrel *i* is connected by a pipe *j*¹ to a reservoir *k* which in turn is connected by a pipe *k*¹ to the suction of a small auxiliary pump *l*, having its piston *m* operated by the crank shaft (not shown in the drawing) which works the main compressor piston *h*. The delivery of this auxiliary pump *l* is connected by the pipe *l*¹ to the pump barrel *i* of the compressor.

The volume swept out by the stroke of the piston *h* is less than that of the compression chamber *d*. In order to complete this volume, so that at the end of the delivery stroke of the piston *h* the diaphragm *c* shall be pressed accurately against the disc *a* carrying the valves *e* *f*, there is injected into the pump-barrel *i* beneath the piston *h*, and through the pipe *l*¹ from the auxiliary pump *l*, a very small quantity of liquid.

At each stroke of the piston *h*, the liquid thus injected escapes either as a result of the leaks at the piston rings, or through the valve *h*¹ in this piston. The excess liquid,

entering the reservoir k , is taken up again by the auxiliary pump l through the pipe k^1 and the suction valve k^2 , being thereafter delivered at the required moment through the valve l^2 and the pipe l^1 into the pump barrel.

This added quantity of liquid, which can be regulated by varying the stroke of the piston m , is injected beneath the main piston h , either during the delivery stroke of the latter, or preferably during the suction stroke.

The liquid coming from the reservoir k , having been heated in the pump barrel i and through the diaphragm e by the compression of the gas, is cooled in any convenient manner before entering the auxiliary pump l and before being delivered into the pump barrel i ; for example, a contra-flow cooler n may be provided in the line of the pipe k^1 and in advance of the suction valve k^2 of the auxiliary pump.

The arrangement according to the invention allows of suppressing the snifter, the return spring of which is difficult to adjust conveniently, and also the variation of the stroke of the compressor piston.

What I claim is:

1. In a diaphragm compressor, of the type in which a pump piston produces, by means of a body of liquid, oscillations of a diaphragm in a chamber of general bi-conical shape, formed between two discs between

which the diaphragm is secured, one of said discs carrying the suction and delivery valves,—the provision of a main pump piston, adapted to generate a volume less than that of the compression chamber, and of a small auxiliary pump, adapted to inject into the main pump barrel, at every stroke of the piston, a small quantity of liquid necessary to complete the volume of the compression chamber and to press the diaphragm against the disc, carrying the valves.

2. In a diaphragm compressor, of the type in which a pump piston produces, by means of a body of liquid, oscillations of a diaphragm in a chamber of general bi-conical shape, formed between two discs between which the diaphragm is secured, one of said discs carrying the suction and delivery valves, the provision of a main pump piston, adapted to generate a volume less than that of the compression chamber, and of a small auxiliary pump, adapted to inject into the main pump barrel on the side remote from the piston rod, at every suction stroke of the piston, a small quantity of liquid necessary to complete the volume of the compression chamber, and to press the diaphragm against the disc carrying the valves.

In testimony whereof I have signed my name to this specification.

HENRI CORBLIN.
